United States Patent Office

Des. 221,937

Patented Sept. 21, 1971

221,937

CHAIR OR SIMILAR ARTICLE

Sidney Gibson, Suite 110, 57 Godstone Road,
Willowdale, Ontario, Canada

Filed Apr. 8, 1970, Ser. No. 22,331

Term of patent 14 years

Int. Cl. D6—02

U.S. Cl. D15—1

FIG. 1

FIG. 2

FIG. 1 is a perspective view taken from the front to one side of a chair embodying my new design, and

FIG. 2 is a perspective view from the rear to the opposite side thereof.

The centre of the chair is broken away to indicate indeterminate length.

I claim:

The ornamental design for a chair or similar article, as shown and described.
